UNITED STATES PATENT OFFICE

1,927,601

PRESSER FOOT FOR SEWING MACHINES

Harry L. Willis, Grand Rapids, Mich., assignor
to Union Special Machine Company, Chicago,
Ill., a corporation of Illinois

Application May 24, 1930. Serial No. 455,389

4 Claims. (Cl. 112—235)

The invention relates to new and useful improvements in a presser foot for a sewing machine, and more particularly to a presser foot known as the roller type.

5 An object of the invention is to provide a presser foot which has a rotating movement imparted thereto by the feed of the fabric, and which is positively held from retrograde movement during the idle stroke of the feeding mechanism.

10 A further object of the invention is to provide a presser foot of the above type which is provided with teeth so shaped as to insure the material being operated upon having a firm gripping contact with the roller foot at all times.

In the drawing:—

Figure 1 is a rear view of a presser foot embodying the invention and showing the position of the same relative to the needle.

20 Fig. 2 is a side view of the same and showing the position and arrangement of the feed dog.

Fig. 3 is a side view of the roller foot.

Fig. 4 is a sectional view on the line 4—4 of Fig. 3.

25 Fig. 5 is a detail showing the supporting member on which the roller foot is mounted.

The invention is directed to a presser foot for sewing machines, and more particularly to a presser foot known as the roller type, that is the

30 fabric engaging portion is in the form of a roller mounted for rotation. This roller is carried by a shank member which is mounted in the usual way on a presser bar. The presser foot roller is provided with teeth which project at the contact portion

35 thereof with the fabric in the direction of the feed of the fabric, and said foot is mounted to turn during the feed of the fabric. Means is associated with this roller foot for preventing retrograde movement thereof. When the feed

40 reaches the end of its stroke and the movement of the fabric in a forward direction ceases, the roller presser foot will remain in this fixed set position and no rearward pull of the fabric on the foot will displace it from the position to which

45 it has been fed by the feeding mechanism.

Referring more in detail to the drawing, the invention is directed to a presser foot of the roller type, which foot is indicated at 1 in the drawing. This roller foot 1 is of course circular in outline, and the peripheral edge of the roller foot is inclined as indicated in the drawing. This enables the presser foot to be set so as to rotate in a plane at an angle to the plane of the work support and therefore it can be set so as to work very close to the needle which is indicated at 3

in the drawing. This roller foot is particularly adapted to be used in connection with glove sewing machines and the material operated upon is referred to as a fabric in the broader sense of the use of this term. The peripheral edge of the 60 presser foot is provided with teeth 4. These teeth 4 are preferably inclined slightly in a counter-clockwise direction as viewed in Fig. 2. The feeding mechanism is preferably of the four-motion type, and includes a feed dog indicated 65 at 5 in the drawing. This feed dog has a movement in the direction of the arrow in Fig. 2 for feeding the fabric which then is disengaged from the fabric and returns through the idle stroke for the next feeding cycle. The feeding mechanism has not been shown as it is of the usual type in a sewing machine. The invention is directed particularly in this case to the mounting of this roller foot so that said roller foot while it is free to turn in a clockwise direction as viewed in 70 Fig. 3 it is held from rotation in a counter-clockwise direction.

The roller foot is mounted on a bracket which includes a sleeve 6 adapted to be secured to the presser bar which of course is mounted for reciprocation in the needle head and spring pressed downwardly in the usual manner. This bracket also includes a laterally projecting arm 7 on which a support 8 is mounted for horizontal adjustment. This support 8 is in two sections pivotally connected and is of a construction similar to that shown in the patent to Long No. 1,625,616, granted April 19, 1927. The supporting shank for the roller is indicated at 9 in the drawing, and this shank is mounted in the support 8. The shank has an opening 10 therethrough and a recess 11 in the outer face of the shank. There is also a pin 12 carried by this shank. The roller foot is provided with a recess 13, and with a hub 14. The hub 14 has an opening therethrough, and is threaded to receive a screw 15. This hub extends through the opening 10, and a washer 16 located in the recess 11 serves as a means for securing the foot to the shank 9. Surrounding the hub 14 is a bearing sleeve 17, which extends into the opening 10. This bearing sleeve is provided with an eccentric headed portion 18 located in the recess 13. Said headed portion has a notch 19 which engages the pin 12. This holds the bearing sleeve from rotation, and also the headed portion carried thereby. This headed portion is circular, but is eccentrically set relative to the center of rotation of the roller foot. A clutch roller 20 is located in the recess 13. The inner face of this recess 13 is cylindrical and is con- 100

110

centric to the center of rotation of the roller foot. A leaf spring 21 is secured to the head 18 of the sleeve 17 and bears on this roller 20 normally imparting a counter-clockwise movement to the roller around the center of rotation of the roller foot. This forces the roller into wedging engagement with the headed portion of the sleeve and the roller foot. Any tendency of the roller foot to turn in a counter-clockwise direction as viewed in Fig. 3 will be prevented by this clutching roller 20 through its wedging engagement with these surfaces. The feed of the fabric is in the direction indicated by the arrow in Fig. 2. As the fabric is fed the roller foot will turn freely in a counter-clockwise direction as viewed in this figure. When the feed dog reaches the end of its stroke any pull of the fabric in a direction opposed to that indicated by the arrow will cause the fabric to be gripped by these teeth 4 of the roller foot and the roller 20 will prevent the roller foot from turning. This insures that the fabric when fed a given distance will be held firmly after the feed dog has been disengaged therefrom, and a uniformity of a feeding of the fabric is thus accomplished.

It will be understood that other ways may be used for mounting the roller than that specifically described. The essential feature resides in a means which will prevent said roller foot from any retrograde movement after the fabric is released by the feed dog at the end of the feed stroke, and at the same time will permit said roller foot to turn freely during the feeding of the fabric. When the fabric is fed the roller 20 will at once release its gripping hold on the surfaces with which it contacts and thus permit the feed roller to turn freely. The spring, however, will yieldingly and lightly hold the roller in contact with these surfaces so that any tendency of the roller foot to turn in a retrograde direction is prevented. It is also obvious that minor changes in the details of the present construction may be made without departing from the spirit of the invention as set forth in the appended claims.

Having thus fully described my invention, what I claim as new and desire to secure by Letters Patent, is:—

50 1. A presser foot for sewing machines comprising a support, a roller foot, a bearing sleeve fixedly carried by said support, said foot having a hub

extending through said sleeve, means attached to said hub for holding said foot on said support so that it may be rotated in the sleeve by the movement of the fabric by the feed, and means associated with said roller foot and bearing sleeve for preventing retrograde movement of the foot. 80

2. A presser foot for sewing machines comprising a support, a roller foot, a bearing sleeve fixedly carried by said support, said foot having a hub extending through said sleeve, means attached to said hub for holding said foot on said support so that it may be rotated in the sleeve by the movement of the fabric by the feed, said roller foot having a recess providing a concentric clutch face, said sleeve having an eccentric clutch face located within said recess, and a clutch member yieldingly forced into engagement with said clutching faces and operating to prevent retrograde movement of the foot. 85 90

3. A presser foot for sewing machines comprising a support, a roller foot mounted thereon and rotated by the movement of the fabric by the feed, said roller foot having teeth projecting at the time of engagement with the fabric in the direction of the feed of the fabric, said roller foot having a recess in the face thereof adjacent the support, a supporting hub, a sleeve fixed to said support in which said hub is mounted, means for holding said hub in said sleeve and the sleeve in said support, and means associated with the roller foot and support for preventing retrograde movement thereof. 95 100 105

4. A presser foot for sewing machines comprising a support, a roller foot mounted thereon and rotated by the movement of the fabric by the feed, said roller foot having teeth projecting at the time of engagement with the fabric in the direction of the feed of the fabric, said roller foot having a recess in the face thereof adjacent the support, a supporting hub, a sleeve fixed to said support in which said hub is mounted, means for holding said hub in said sleeve and the sleeve in said support, said sleeve having a head provided with an eccentrically arranged clutch face, said roller foot having a concentric clutch face, a clutch roller located between said faces, and a spring forcing said roller into contact with the clutch faces, said clutch faces being disposed so as to prevent retrograde movement of the roller foot. 110 115 120 125
